UNITED STATES PATENT OFFICE

2,304,401

ADAPTER UNIT FOR LOOSE-LEAF BINDERS

George S. Emery, Tulsa, Okla.

Application January 30, 1942, Serial No. 428,939

3 Claims. (Cl. 129—1)

This invention relates to loose leaf binders and has for its object to provide means for converting binders of the single post type into binders of the double-post or inverted-U type.

The present invention represents an improvement upon the invention disclosed in my Patent No. 2,093,041, granted September 14, 1937. In my former patent I described and claimed an adapter comprising a sheet-metal casing so constructed and arranged to be slipped or sprung over an end of the bottom cover of a conventional loose leaf binder of the single post type and designed to cooperate with the structure thereof so as to allow its reconstruction into a binder of the double-post type. While such form of adapter serves satisfactorily in connection with most styles of single-post binders, it is subject to the disadvantage that an adapter suitable for one or two different sizes of binder is not capable of use with other sizes of binders because of the variation in the spacing between the pair of binding posts provided on such single-post binders.

The present invention has for one of its important objects to overcome the above objection by providing individual adapter units each constructed and arranged to be slipped over an end of the bottom cover of a single-post binder so as to cooperate with the opening in the cover originally occupied by one of the binding posts and permit assembly therewith of a binding post of the inverted-U type. By virtue of this construction a wide field of application of my device with different styles and types of binders is provided.

Another object of my invention is to provide an adapter unit of the above character that is capable of being readily built up to different thicknesses so as to correspond to the thickness of the cover with which the units are to be associated.

Still another object of my invention is to provide an adapter unit which is simple in construction and capable of being economically manufactured.

Other objects and advantages will be apparent from the following detailed description of a preferred embodiment of my invention, reference being had to the annexed drawing, in which:

Figure 1 is a perspective view of a loose-leaf binder cover showing one of the adapter units associated therewith;

Figure 2 is a vertical cross-sectional view through the adapter unit of Fig. 1;

Figure 3 is a side view of a modified form of

the adapter unit associated with an end of a binder cover; and

Figure 4 is a side view of still another modification of the adapter unit.

Referring to Figs. 1 and 2 of the drawing, the adapter unit 1 comprises a pair of flat elongated metal plates 2 and 2a partly overlying the top and bottom surfaces, respectively, of a bottom cover B of a loose leaf binder, this cover being provided with a pair of spaced apart holes 3 which, in conventional binders of the single-post type, receive the lower ends of the posts upon which the papers to be associated with the binder are filed.

15 The plates 2 and 2a are maintained in spaced relation by means of a spacer block 4 interposed therebetween and composed of a plurality of superposed spacer shims 4a. The plates and shims composing the spacer block are held in assembly by means of a screw 5 extending through openings therein and threadedly connected to the lower plate 2a, as best illustrated in Fig. 2. The shims 4a are substantially shorter in length than the plates 2 and 2a and terminate even with said plates at one end. The plates 20 and spacer block are provided with registering openings together providing a hole 6 through which passes the lower end of one of the posts 7 of a double-post filing unit 8. The lower end of this post projects beyond the lower plate 2a and is threaded to receive a nut 9 for securing the post to the adapter unit.

25 The upper and lower plates 2 and 2a are provided with openings adapted to register with the hole 3 originally provided in the cover B and a companion post 7a of the double-post filing unit 30 passes through these registering openings and hole and is secured in assembly with the cover by means of a nut 10 threadedly associated with the projecting lower end of this post.

35 The posts 7 and 7a of the filing unit may comprise individual sections 11 threadedly connected together and including a bridging member 11a pivoted upon the upper end of the post 7 and adapted to swing into and out of engagement with the upper end of the companion post 7a, as more fully described in my prior patent referred to above. However, this filing unit may be of any other suitable construction. It will be understood that a pair of adapter units will be associated with the cover, one for each hole 3 from which the original post has been removed, and that when so associated the conversion of the binder from the single post type to the double-post or inverted-U type will be complete.

In order to avoid play between the adapter units and the cover, the units may be fastened to the cover by screws 12 passing through openings in the top plate 2 into the cover. In assembling the adapter units with the lower cover a suitable number of shims will be used to correspond to the thickness of the cover, which thickness will vary with different styles of binders.

Another form of my adapter unit is illustrated in Fig. 3. In this embodiment the adapter unit corresponds in all respects to the unit of Figs. 1 and 2 except that the companion upper and lower plates 2 and 2a are provided with in-turned ends together forming an intermediate section 2c. The section 2c serves as a shield for the outer end of the spacer block 4, thus contributing a neater and more finished appearance to the adapter unit.

Figure 4 shows another form that my adapter unit may take. In this modification, the adapter unit, like the adapter unit of Fig. 3, has its companion upper and lower plates 2 and 2a formed with in-turned ends to define a shielding section 2c for the spacer block 4'. The spacer block is composed of a solid piece of wood or metal permanently secured to one or both of these plates so that the top plate, bottom plate and spacer block may be sold as a unit and thus arranged to be quickly assembled with the cover. If desired, these parts may be cast as a unitary piece.

It is within the scope of my invention to employ any suitable form of bridging member 11a. For example, it may be spring attached for raising or lowering to open and close the connection between the posts; it may be made loose so as to lift out; or it may be pivotally connected to its supporting post. Alternatively it may be provided with magnetized ends for magnetic association with the posts, the essential condition being that this bridging member may be opened and closed with facility, without becoming loose or accidentally separated, and allow papers to be added to or removed from the binder quickly and easily.

In some types of single post binders the holes 3 do not extend entirely through the cover but are internally screw-threaded to provide sockets for receiving the threaded ends of the binding posts. When such is the case the projecting threaded lower end of the post 7a of my filing unit may be made suitably short so as to screw into this socket and be retained thereby. For the reason that the upper plate 2 is rigidly fastened to the cover by the screws 12, it is structurally immaterial whether or not the end of post 7a extends completely through the cover. The threaded lower ends of posts 7 also may vary in length to correspond to the length of the threaded lower ends of the companion posts 7a; and in the event they are made shorter than the thickness of the spacer block, they may screw into the hole 6, which latter may be internally screw-threaded to receive them.

It will be apparent that the adapter unit is capable of being embodied in forms other than those described above without departing from the spirit of my invention as defined in the following claims.

I claim:

1. An adapter unit designed to convert binders of the single post type into binders of the double-post type, comprising an elongated upper plate and an elongated lower plate adapted to overlie the upper and lower surfaces of a binder cover and extend beyond the end of the cover, said plates being of substantially less width than the cover with which it is designed to be assembled and each being provided with an opening adapted to register with a post hole originally provided in the cover, a spacer block intermediate said plates and maintaining said plates in substantially parallel spaced relation, said spacer block being materially shorter in length than the plates and located between those portions of the plates adapted to extend beyond the end of the cover, and a hole through said plates and spacer block cooperatively located with respect to said openings, whereby a pair of posts of a double-post filing unit may be mounted in said hole and openings for securing the adapter unit to said cover.

2. An adapter unit designed to convert binders of the single post type into binders of the double-post type, comprising an elongated upper plate and an elongated lower plate adapted to overlie the upper and lower surfaces of a binder cover and extend beyond the end of the cover, said plates being of substantially less width than the cover with which it is designed to be assembled and each being provided with an opening adapted to register with a post hole originally provided in the cover, a spacer block intermediate said plates and maintaining said plates in substantially parallel spaced relation, said spacer block being materially shorter in length than the plates and located between those portions of the plates adapted to extend beyond the end of the cover, and a hole through said plates and spacer block cooperatively located with respect to said openings, whereby a pair of posts of a double-post filing unit may be mounted in said hole and openings for securing the adapter unit to said cover.

3. An adapted unit designed to convert binders of the single post type into binders of the double-post type, comprising an elongated upper plate and an elongated lower plate adapted to overlie the upper and lower surfaces of a binder cover and extend beyond the end of the cover, said plates being of substantially less width than the cover with which it is designed to be assembled and each being provided with an opening adapted to register with a post hole originally provided in the cover, a spacer block intermediate said plates and maintaining said plates in substantially parallel spaced relation, said spacer block being materially shorter in length than the plates and located between those portions of the plates adapted to extend beyond the end of the cover, and a hole through said plates and spacer block cooperatively located with respect to said openings, whereby a pair of posts of a double-post filing unit may be mounted in said hole and openings, said spacer block comprising a plurality of superposed shims adapted to be selectively assembled to vary the thickness of the spacer block.

GEORGE S. EMERY.
